JOHN H. WELLER, OF NEW HAVEN, CONNECTICUT, ASSIGNOR TO SARGENT & COMPANY,
OF NEW HAVEN, CONNECTICUT

CORK EXTRACTOR AND BOTTLE OPENER

Application filed May 10, 1929. Serial No. 361,938.

My invention relates to a cork extractor and bottle opener, and more especially to a cork extractor and bottle opener by means of which corks and other sealing devices may be removed from the necks of bottles without mutilation.

The usual cork extractor comprises a screw which is threaded into the cork and the cork removed by an axial pull on the extractor. It quite often happens that the frictional resistance between the cork and bottle neck is greater than the resistance offered to the withdrawal of the screw from the cork, with the result that the screw is pulled out of the cork, leaving the latter in a mutilated condition in the bottle.

One of the objects of the present invention is to provide a cork extractor in which the frictional resistance of the cork in the bottle neck is overcome as an axial force is applied to the cork in order that the latter may be readily withdrawn without mutilation.

Another object of the invention is to provide an extractor having the above features which may accommodate itself to corks of various diameters.

A further object of the invention is to provide a device by means of which sealing devices of different characters may be readily separated from the necks of bottles.

A feature of the invention resides in a novel means for suspending the improved cork extractor and bottle opener from a nail or the like when the improved cork extractor and bottle opener is not in use, the suspending means being foldable out of the way when the device is in use.

To these and other ends, the invention consists in the novel features and combination of parts to be hereinafter described and claimed.

In the drawing,

Fig. 1 is an elevational view, showing a cork extractor and bottle opener according to my invention;

Fig. 2 is a view similar to Fig. 1, but showing the opposite side of the cork extractor and bottle opener;

Fig. 3 is a side view of the same;

Fig. 4 is a sectional view along line 4—4 of Fig. 2;

Fig. 5 is a sectional view along line 5—5 of Fig. 2;

Fig. 6 is a view showing the cork extractor in operative engagement with a cork in the neck of a bottle; and

Fig. 7 is a view partly broken away, showing the device in use in withdrawing a cap from the neck of a bottle.

Referring to the drawing in which I have illustrated my invention by showing a preferred embodiment of the same, the reference numeral 10 indicates in general my improved cork extractor and bottle opener, which comprises generally speaking a handle 11, a cork extracting part 12, a bottle cap removing part 13, and a hanger 14. The handle 11, which may conveniently take the form of a casting of any suitable material, is provided with laterally extending arms 15 and 16, which may be surrounded by the fingers of an operator during the act of withdrawing a cork. On the lower end of handle 11 is a shank 17 in which are secured a pair of arms 18 and 19 of the cork extracting part 12. Preferably the arms 18 and 19 are formed out of a single strip of material doubled over at 20, the handle 11 being preferably cast around the doubled over part 20, as shown in Fig. 1, in order to firmly anchor the cork extracting part 12 to the handle.

Arms 18 and 19 as they emerge from handle 11 curve inwardly towards one another to points 21 and 22, and then curve outwardly to points 23 and 24, and then taper slightly towards one another until at their ends 25 and 26 they again curve outwardly, arm 19 being slightly shorter than arm 18. As shown in Fig. 5 of the drawing, the ends of arms 18 and 19 beyond points 23 and 24 are curved in cross-section to present inner concave and outer convex surfaces, while the remainder of the strip from which the cork extracting part is formed is relatively flat.

The operation of the device in pulling or extracting corks is as follows: The end 25 of arm 18, the latter being longer than arm 19, is inserted between the inner surface 27 of neck 28 of bottle 29 and the surface of

cork 30, and then the end 26 of arm 19 is inserted between the cork 30 and the surface 27 of neck 28 at a point diametrically opposite arm 18, whereupon the two arms are 5 pressed downwardly between the cork and bottle neck and beyond the end of the cork into the position shown in Fig. 6 of the drawing, or slightly beyond this position, the inwardly curved parts above points 23 and 24 10 limiting the amount the arms may be inserted into bottle by contacting with the upper end of the cork. The lateral extensions 15 and 16 are grasped by the fingers of the operator and the extractor is withdrawn by a combined rotary and upward movement of the 15 extractor in neck 28, the cork being loosened from the neck of the bottle and withdrawn therefrom as the extractor moves upwardly. The outwardly curved portions 25 and 26 on 20 the lower ends of the arms 18 and 19 guide the latter between the cork and bottle neck and overcome any tendency of the arms to enter the cork, while the transverse curvature of the arms permits the latter to be readily rotated in the bottle neck and to efficiently grip the cork.

Handle 11 is inwardly concave at 31 and provided near its upper end with an outwardly extending arm 32 having a downwardly projecting lug 33 which may engage a cap 34^a (Fig. 7) of bottle 34 to remove the latter by downward pressure on arms 18 and 19.

The hanger 14 comprises a ring 35 bent out 35 of resilient wire or the like, and having integrally formed therewith spaced arms 36 and 37 provided with lateral extensions 38 and 39, which enter and are pivotally mounted in openings 40 and 41 in handle 11, the 40 latter being cored out at 42 and 43 so that the hanger may be folded into the handle. The handle is cut away at 44, so that the finger nail of the operator or a suitable tool may be inserted under the hanger in order to swing 45 the latter into operative position, wherein the cork extractor and bottle opener may be suspended from a nail or hook when not in use.

From the above description of the nature 50 and operation of my improved cork extractor and bottle opener, it will be readily seen that I have provided a device which may efficiently withdraw corks and caps of any size 55 within the scope of the tool from bottles without mutilation, and which is simple in form having no parts which are apt to get out of order.

While I have shown and described a preferred embodiment of my invention, it will be understood that it is not to be limited to all the details shown, but is capable of modification and variation within the spirit of the invention and the scope of the appended 65 claims.

What I claim is:—

1. In a device for withdrawing corks from the necks of bottles or the like, a solid handle having a shank and integrally formed laterally extending arms, and a pair of cork 70 gripping fingers extending downwardly from the shank and adapted to engage a cork seated in the neck of a bottle by insertion into the bottle between the neck and cork, said fingers being made out of a single strip of resilient material looped intermediate its ends, the looped part being embedded in the shank, said fingers curving inwardly toward one another adjacent the shank and then immediately outwardly away from one another. 75

2. In a device for withdrawing corks from the necks of bottles or the like, a solid handle having a shank and integrally formed laterally extending arms, and a pair of cork gripping fingers extending downwardly from the shank and adapted to engage a cork seated in the neck of a bottle by insertion into the bottle between the neck and cork, said fingers being made out of a single strip of resilient material looped intermediate its ends, the looped part being embedded in the shank, said fingers curving inwardly toward one another adjacent the shank and then immediately outwardly away from one another, 80 said fingers being relatively flat in cross-section at their ends and adjacent the shank and of curved cross-section between the inwardly curved parts and their ends. 85

In witness whereof, I have hereunto set my hand this 4 day of May, 1929.

JOHN H. WELLER.
